(57) **CLAIM**

The ornamental design for a gaming system symbol display, as shown and described.

DESCRIPTION

FIG. 1 is a front perspective view of a gaming system symbol display of my new design, that portion shown in

phantom is not part of the design sought to be patented and is provided for environmental purposes only.

FIG. 2 is a left side view of the gaming system symbol display of my new design of FIG. 1, the right side being a mirror image thereof, that portion shown in phantom is not part of the design sought to be patented and is provided for environmental purposes only.

FIG. 3 is an front view of the gaming system symbol display of my new design of FIG. 1, that portion shown in phantom is not part of the design sought to be patented and is provided for environmental purposes only.

FIG. 4 is a back view of the gaming system symbol display of my new design of FIG. 1, that portion shown in phantom is not part of the design sought to be patented and is provided for environmental purposes only.

FIG. 5 is a top plan view of the gaming system symbol display of my new design of FIG. 1, that portion shown in phantom is not part of the design sought to be patented and is provided for environmental purposes only.

FIG. 6 is a front perspective view of an alternative embodiment of the gaming system symbol display of my new design, that portion shown in phantom is not part of the design sought to be patented and is provided for environmental purposes only.

FIG. 7 is a left side view of the alternative gaming system symbol display of my new design of FIG. 6, the right side being a mirror image thereof, that portion shown in phantom is not part of the design sought to be patented and is provided for environmental purposes only.

FIG. 8 is an front view of the gaming system symbol display of my new design of FIG. 6, that portion shown in phantom is not part of the design sought to be patented and is provided for environmental purposes only.

FIG. 9 is a back view of the gaming system symbol display of my new design of FIG. 6, that portion shown in phantom is not part of the design sought to be patented and is provided for environmental purposes only; and,

FIG. 10 is a top plan view of the gaming system symbol display of my new design of FIG. 6, that portion shown in phantom is not part of the design sought to be patented and is provided for environmental purposes only.
